UNITED STATES PATENT OFFICE.

WILLIAM J. KNOX, OF DUBOIS, PENNSYLVANIA, ASSIGNOR TO WALTER P. MURPHY,
OF CHICAGO, ILLINOIS.

UNCOUPLING ATTACHMENT.

1,123,555.

Specification of Letters Patent.

Patented Jan. 5, 1915.

Original application filed April 29, 1911, Serial No. 624,176. Divided and this application filed August 28, 1914. Serial No. 858,689.

To all whom it may concern:

Be it known that I, WILLIAM J. KNOX, a citizen of the United States, residing at Dubois, in the county of Clearfield and State of Pennsylvania, have invented certain new and useful Improvements in Uncoupling Attachments, of which the following is a specification.

The invention relates to uncoupling attachments for use with the automatic couplers employed on railway cars.

The primary objects of the invention are; to produce an uncoupling device which will allow for all buffing and draft movements, lateral movements and vertical movements of the draw head; to produce an uncoupling mechanism which is capable of operation as closely as possible to the body of the car and in which all parts are attached to the car; the provision of an improved positive form of flexible connection wherein the use of chains, loose links and similar devices are avoided; the provision of an uncoupling rigging capable of use with the brackets now employed with old and unsatisfactory forms of rigging; the provision of a release rigging which may be formed of common bar iron or steel so simply manufactured and assembled that highly skilled labor is not required; and the provision of apparatus in which the rigging may be detached from the coupler without detaching the brackets carrying the rigging.

A further object of my invention is to provide a release rigging so constructed and mounted, that in case of disconnection between any of the parts, each part will remain attached to the car; and with these and other objects in view my invention consists of the parts or combination of parts as will be hereinafter pointed out.

In the drawing Figure 1 is a top plan view of a release rigging embodying my invention, shown attached to a car, the car being in section. Fig. 2 is a front elevation of the same.

The reference numeral 1 designates a portion of a car, 2 the draw head and 3 coupler pin operating in the draw head and provided with an eye through which the lifting link or lever may freely pass as will hereinafter be fully pointed out.

The attaching brackets 4 and 5 are securely fixed directly to the car in any suitable manner and are each provided with an eye or opening in which the hand operated lever 6 is revolvably mounted, said lever being provided with a depending crank arm 7 at its outer end and with a lifting arm 8 extending laterally therefrom which arm is bent downward as at 9 and thence outward to receive upon said outwardly extending portion the laterally extending arm of the lifting link or lever where it is retained. 55 The lifting link or lever comprising a relatively long portion 10^a and a relatively short portion 12^a at right angles to each other is connected directly to the car by means of a bracket 11 permanently secured to the car 70 which prevents the loss of the lifting lever, said bracket having an eye through which the relatively short depending portion 12 12^a of the lifting link or lever extends, and is secured therein by any suitable means, 75 such for instance as a cotter pin 13; the relative diameter of the opening in the bracket 11 and the diameter of the short depending portion 12 being such that the arm 12 has universal play thereby. The bracket 80 11 permits the lifting lever to swing to and from the car with the draw head in buffing and draft during which movement the lifting lever travels upon the lifting arm 8.

The inner end of the lifting link 10 is 85 passed through the eye of the pin 3 and the pin may slide thereon to accommodate the lateral movements of the draw head, the extreme inner end being bent to one side as at 14. The fact that the lifting lever is 90 provided with a relatively short depending portion 12 enables me to position the relatively long arm 10^a of the lifting lever close to the hand operating lever 6 without said operating lever being interfered with by 95 the bracket 5 which secures the lifting lever to the car. This fact enables me to substitute the lifting lever herein shown for other types of pin lifting means and utilize the hand operated lever so commonly used on 100 cars for operating the coupler pin by levers and chains.

This is a division of my application filed April 29, 1911, Serial No. 624,176.

What I claim is:

1. In an uncoupling device for car cou-

105

2

plers, the combination with a pin lifting lever having a relatively long and a relatively short portion at right angles to each other, and connected directly to a car, of a 5 rotatable operating lever attached to the end of a car with its inner end extending beyond the point of attachment of the pin lever and provided with a lifting arm extending outwardly beneath the relatively longer 10 portion of the pin lever, the lifting arm co-operating with the pin lever for the purpose described.

2. In an uncoupling mechanism for car 15 couplers, the combination with a pin lifting lever having a relatively long portion and a relatively short portion at right angles to each other, a device for loosely pivotally connecting the free end of the short portion to the car, of a rotatable operating lever 20 attached to the end of a car and provided at its inner end with a lifting arm extending outwardly and beneath the long portion of

the pin lever, and coöperating with the pin lever for the purpose set forth.

3. In an uncoupling device for car couplers, the combination with a pin lifting lever having a relatively long portion and a relatively short portion at right angles to each other, said short portion having a depending portion having a direct flexible 25 connection with a car, of a rotatable operating lever attached to the end of a car with its inner end extending beyond the point of attachment of the pin lifting lever and provided with a lifting arm extending 30 outwardly beneath the relatively longer portion of the pin lever, and coöperating with the pin lever for the purpose set forth.

In testimony whereof I affix my signature in presence of two witnesses.

WILLIAM J. KNOX.
